George D. Sprecher, of Lancaster, Pa.
Letters Patent No. 1071, Dated Dec. 7, 1858.

The schedule referred to in these Letters Patent and making part of the same.

To all whom it may concern:

Be it known that I, George D. Sprecher, of the City and County of Lancaster in the State of Pennsylvania, have invented or produced a new and original design and pattern for casting stove plates in ornamental bas. relief, expressly made for a combined wood and coal stove, called the "New dining room cook-stove".

And I do hereby declare that the following is a full and clear description and representation of the same, reference being had to the accompanying drawings making a part of this specification in which

Fig. 1. is a front side and front end perspective view, showing the long upper oven door with its central ventilator and bas. relief figures, the lower oven door, fire door and little or name, as also the oblong square between the fire door and draft above the Ash pan.

Fig. 5. the grated sliding fender or ash hole cover, lettered "New dining room cook", also the projecting base, on the broad front. On the side below is shown a door, used when burning long wood. and a panel similarly ornamented, above it of equal dimensions.

Fig. 2. represents the broad back end with its three ornamented panels.
Fig. 3. the narrow back end and its ornamented panels.

In order to prevent others from using my plates as patterns thereby avoiding the expense incurred by me in producing the patterns for casting the same. I desire the same to be secured to me by letters patent.

What I claim as my production are the ornamental Bas. relief figures on the several doors and panels when combined and arranged substantially as represented in the accompanying drawings.

End Witnesses.
